UNITED STATES PATENT OFFICE

FRANK M. VOGAN, OF CANTON, OHIO, ASSIGNOR TO THE REEVES MANUFACTURING COMPANY, OF DOVER, OHIO, A CORPORATION OF OHIO

DESIGN FOR A WASHTUB

Application filed February 9, 1933. Serial No. 47,155. Term of patent 14 years.

To all whom it may concern:

Be it known that I, FRANK M. VOGAN, a citizen of the United States, residing at Canton, in the county of Stark and State of Ohio, have invented a new, original, and ornamental Design for Wash Tubs, of which the following is a specification, reference being had to the accompanying drawing, forming part thereof.

Figure 1 is a top plan view of a wash tub,

Fig. 2, a side elevation of a wash tub, showing my new design.

I claim:

The ornamental design for a wash tub, as shown.

FRANK M. VOGAN.
